UNITED STATES PATENT OFFICE.

JOHN M. YOUNG AND CLARENCE M. SYMONDS, OF SAN FRANCISCO, CALIFORNIA, ASSIGNORS TO AMERICAN CAN COMPANY, OF NEW YORK, N. Y., A CORPORATION OF NEW JERSEY.

SHEET-METAL CAN.

No. 799,820.

Specification of Letters Patent.

Patented Sept. 19, 1905.

Application filed March 18, 1905. Serial No. 250,724.

To all whom it may concern:

Be it known that we, JOHN M. YOUNG and CLARENCE M. SYMONDS, citizens of the United States, residing in San Francisco, in the county of San Francisco and State of California, have invented a new and useful Improvement in Sheet-Metal Cans, of which the following is a specification.

Our invention relates to improvements in sheet-metal cans.

The object of our invention is to provide a can of a simple, efficient, durable, and economical construction and having a removable cover for opening and closing the can as the contents are used and provided with a protective frangible seal adapted to bear the name or trade-mark of the manufacturer of the material in the can and which requires to be broken or destroyed before the can can be opened, and thus guard against the can being again refilled with spurious or inferior goods and palmed off under the original label on the can as genuine, and in which the frangible seal may be applied at the can-factory where the cans are made and wherein also the frangible seal will be prevented from all danger of breakage or injury during handling and shipment of the empty cans from the factory to the packing-house where the cans are filled.

Our invention consists in the means we employ to practically accomplish this object or result—that is to say, it consists in a can having a top or head at one end furnished with a removable cover adapted to open and close the can as its contents are being used and with a protective seal of paper, parchment, or other thin easily-removable material and adapted to bear the name or trade-mark of the manufacturer or person putting up the goods in the can, the frangible seal being permanently secured to the can or its head and fitting directly against and protected from breakage or injury by the removable cover of the can, said can having a bottom head adapted to be seamed or otherwise secured to the body after the can has been filled.

Our invention further consists in a friction-top can having a top or head furnished with a seat for a friction-cover, and a friction-cover for closing the opening in said friction-top, and a frangible seal seamed or secured to said friction-top inside the friction-cover, said can being adapted to be filled through the lower

or bottom end and having a bottom head secured or adapted to be secured thereto after the can is filled.

Our invention also consists in the novel construction of parts and devices and in the novel combinations of parts and devices herein shown or described.

In the accompanying drawings, forming a part of this specification, Figure 1 is a vertical sectional view of a can embodying our invention. Fig. 2 is a top or plan view. Fig. 3 is a top or plan view with the removable or friction-cover removed. Fig. 4 is a detail sectional view showing the top head of the can with friction-cover applied before said friction top or head is seamed to the can-body. Fig. 5 is a detail sectional view of the removable-cover-receiving top or head of the can before being secured to the can-body and before the removable cover is applied. Fig. 6 is a sectional view of the can after it has been filled and before its bottom head is seamed or secured to the body thereof. Fig. 7 is a sectional view showing a modification. In the sectional views the thickness of the parts and the clearance-space between adjacent parts are exaggerated for clearness of illustration.

In the drawings, A represents the can-body of any suitable kind or form.

B is the removable-cover-receiving head or top, the same having a large opening B' therein, adapted to be closed by a removable cover D, the head or top B being preferably a friction top or head and the removable cover D being preferably what is commonly known in the art as a "friction-cover," and C is the bottom head of the can, which is seamed or otherwise secured to the body after the can is filled.

F is the frangible protective seal, the same being permanently seamed or secured to the top or head B of the can and fitting just inside and against or closely adjacent to the removable cover D and supported and protected from perforation, breakage, or injury by said removable cover.

The can-body A is preferably provided with an outwardly-projecting seaming-flange *a* at its bottom or filling end, adapted to be folded into a double, rolled, or other seam *a'* with the seaming-flange *c* of the bottom head C after the can is filled. The can-body A is also preferably provided at its other end with an ex-

ternally-projecting seaming-flange a^2 , adapted to be folded or rolled into a double or other seam a^3 with the seaming-flange b of the removable-cover-receiving head B of the can.

- 5 The removable-cover-receiving head B of the can is preferably countersunk or furnished with a depending flange b' , thus forming a channel to receive the end of the can-body and a raised shoulder or rim b^2 at the 10 upper end of the can-body when the head B is seamed to the body. The removable-cover-receiving head B is further preferably provided with a depending cover-seat wall or flange b^3 , adapted to tightly engage the corresponding wall or flange d of the removable cover D and form a tight and secure joint therewith. The frangible protective paper, parchment, or other thin material seal F may be permanently secured to the head B over 15 the opening B' therein by any suitable means. We prefer, however, to so secure the frangible seal F to the head B by means of a sheet-metal connecting-ring G , snugly fitting and surrounding the friction-seat wall or flange b^3 of the friction-top B and having a horizontal inwardly-projecting flange g furnished with folds or flanges $g' g''$, between which the edge or rim of the frangible seal F is clamped. In the modification illustrated in Fig. 7 the 20 frangible seal F is permanently attached to the head B by means of connecting-ring G' , having a single flange g , between which and the lower edge of the flange b^3 of the top or head B the frangible seal F is clamped. The 25 ring G in both constructions is forcibly pressed upon and surrounds the depending flange or wall b^3 of the removable-cover-receiving head B . The removable cover D is preferably furnished, in addition to the depending wall or flange d , with a horizontally-projecting rim d' , having a fold d^2 at its outer edge to strengthen the same and enable the cover to be readily pried off by any suitable lever or tool over the shoulder b^2 at the top edge of 30 the can as fulcrum, thus enabling the can to be easily opened.

The frangible seal F is preferably made of paper or parchment-paper and may have printed or stamped thereon any suitable trade-mark or name indicating the manufacture or origin of the goods contained in the can.

The can as manufactured at the can-factory has the head B , with the frangible seal F firmly attached thereto, permanently seamed 35 to the can-body and also the removable cover D securely seated in the head B , thus securely protecting the frangible seal F from mutilation or injury. After the can is filled the bottom head C is likewise seamed to the can-body. The filled can now cannot be opened or its contents used without first removing the removable cover D in the usual manner and then destroying the frangible protective 40 and goods-identifying seal F ; nor can the can be again refilled with spurious articles and

again used, as another frangible seal F cannot be applied to the head B after said head B has once been seamed to the can-body.

We claim—

1. In a can or vessel, the combination with 70 a body and a removable cover-receiving head secured to the body, a removable cover closing the opening in said head, a connecting-ring secured to said head, and a frangible protective seal secured to said head inside the 75 same by said connecting-ring, substantially as specified.

2. In a can or vessel, the combination with 80 a body and a removable cover-receiving head secured to the body, a removable cover closing the opening in said head, a connecting-ring secured to said head, a frangible protective seal secured to said connecting-ring inside said cover and head, substantially as specified.

3. In a can or vessel, the combination with 85 a body and a removable cover-receiving head secured to the body, a removable cover closing the opening in said head, a frangible protective seal and a connecting-ring secured to 90 said head and having clamping-flanges embracing said frangible protective seal, substantially as specified.

4. A can or vessel having a sheet-metal friction-head provided with a removable cover- 95 engaging wall, a removable friction-cover closing the opening in said friction-head, and a frangible seal secured to said head, a connecting-ring secured to said head inside the same inside said friction-cover by said connecting-ring, substantially as specified.

5. A can or vessel having a sheet-metal friction-head provided with a removable cover-engaging wall, a removable friction-cover closing the opening in said head inside said 105 friction-cover, a frangible seal inside said cover and a connecting-ring having flanges between which said seal is clamped, substantially as specified.

6. A can or vessel having a sheet-metal friction-head provided with a removable cover-engaging wall, a removable friction-cover closing the opening in said head, a frangible seal inside said friction-cover and protected thereby, and a connecting-ring secured to said 115 friction-head and to which said seal is secured, substantially as specified.

7. A can or vessel having a sheet-metal friction-head provided with a friction-seat wall, a removable friction-cover closing the opening in said head, a paper seal inside said friction-cover, and a connecting-ring fitting and surrounding said friction-seat wall or flange of the head to which ring said paper seal is secured, substantially as specified.

J. R. MAGILL,
CHARLES STOUT.

It is hereby certified that in Letters Patent No. 799,820, granted September 19, 1905, upon the application of John M. Young and Clarence M. Symonds, of San Francisco, California, for an improvement in "Sheet-Metal Cans," an error appears in the printed specification requiring correction, as follows: On page 2, line 98, after the word "head" the clause "a connecting-ring secured to said head inside the same" should be stricken out and inserted after the word "friction-head," in line 97, same page; and that the said Letters Patent should be read with this correction therein that the same may conform to the record of the case in the Patent Office.

Signed and sealed this 10th day of October, A. D.; 1905.

[SEAL.]

F. I. ALLEN,
Commissioner of Patents.
